No. 14,125

July 24, 1883,

UNITED STATES PATENT OFFICE.

ACHILLE MONIOT, OF PHILADELPHIA, PENNSYLVANIA, ASSIGNOR TO ALLEN & CO., OF SAME PLACE.

DESIGN FOR TWO-PLY UPHOLSTERY.

SPECIFICATION forming part of Design No. 14,125, dated July 24, 1883.

Application filed June 25, 1883. Term of patent 3½ years.

To all whom it may concern:

Be it known that I, ACHILLE MONIOT, a citizen of the United States, residing at Philadelphia, in the county of Philadelphia and State of Pennsylvania, have invented and produced a new and original design for a pattern to be wrought in two-ply upholstery tapestry or damask woven with two warps and two wefts, in such colors or shades of materials as may be desired; and I do hereby declare that the photographic print accompanying this specification conveys to any one skilled in the art of weaving upholstery tapestry and damask a clear understanding of the same, and is sufficient to enable such person to use my invention.

What I claim as my invention, and desire to secure by Letters Patent, is—

The design for upholstery tapestry or damask, as shown in the photographic print accompanying this specification.

ACHILLE MONIOT.

Witnesses:

JOHN SHIMM,

JOSEPH WHITELEY.

It is hereby certified that in Letters Patent No. 14,125, granted July 24, 1883, upon the application of Achille Moniot, of Philadelphia, Pa., for a design for a "Two-Ply Upholstery," the name of the assignee and grantee was written and printed "Allen & Co.;" that said name should have been written and printed Samuel Allen & Co.; and that the proper correction has been made in the files of the case in the Patent Office, and should be read in the grant to make the same conform therewith.

Signed, countersigned, and sealed this 7th day of August, A. D. 1883.

[SEAL.]

M. L. JOSLYN,
Acting Secretary of the Interior.

Countersigned:

E. M. MARBLE,
Commissioner of Patents.
